UNITED STATES PATENT OFFICE.

CHARLIE C. SHETTERLY, OF FRANKLIN, INDIANA.

LOCK FOR AUTOMOBILES.

1,369,559.

Specification of Letters Patent. Patented Feb. 22, 1921.

Application filed November 29, 1919. Serial No. 341,381.

To all whom it may concern:

Be it known that I, CHARLIE C. SHETTERLY, a citizen of the United States, residing at Franklin, in the county of Johnson 5 and State of Indiana, have invented a new and useful Improvement in Locks for Automobiles, of which the following is a specification.

The object of my invention is to provide 10 a novel and effective device adapted to be operated from the dashboard of an automobile to control the fuel supply and shut the same off entirely so as to lock the car against unauthorized use; and it is my object to provide a comparatively simple 15 device adapted to operate with accuracy and positiveness to perform the required operation. I attain these and other objects of my invention by the mechanism illustrated 20 in the accompanying drawings, in which—

Figure 1 is a view of the device in elevation applied to the appropriate part of an automobile;

Fig. 2 is a detailed sectional view of the 25 dashboard and the parts of the lock connected therewith;

Fig. 3 is a longitudinal sectional view of the locking valve and adjacent parts;

Fig. 4 is a side elevation of a modified 30 form of the lock independent of the dashboard mechanism; and

Fig. 5 is a longitudinal section of the device shown in Fig. 4, with parts in elevation.

Like numerals designate like parts 35 throughout the several views.

Referring to the accompanying drawings, Figs. 1-3 represent the preferred form of my invention constructed for operation 40 from the dashboard of an automobile. Mounted in the dashboard is a suitable lock 4 and key 5 (a Yale lock preferably being employed). The lock shank or bolt 24 engages in a driving sleeve 23 which is mounted 45 in a suitable and preferably metallic tube 22 which extends into my lock casing 25. Driving sleeve 23 is composed of a series of links, making it a flexible operating member. The lower end of member 23 is attached to a suitable L-shaped plunger 6 which is operatively in contact with a pivotally mounted pressure plate 7, which in turn is in operative contact with a suitable bell-crank lever 11, one arm of which contacts with the apex (when in closed posi-

tion) of the novel double conical valve 13 which seats in the fuel passage 1 at its point of communication with channel 2 which is connected with the carburetor in some suitable manner. A suitable channel 60 3 is in communication with the gas tank.

Mounted within channel 2 I provide a suitable channel nut 17 which provides a stop for spring 16, which presses against the stem of the double conical valve 13 to 65 press the same normally away from its seat 14 toward bell-crank lever 11, which latter member is swingable on the pivot 12 and has its upper arm engaging diaphragm 10 and bearing against pressure plate 7 which 70 is pivoted on the pivot 8 mounted in the threaded ring 9 of the casing member 20. I provide a suitable joint 18 in threaded engagement with member 20, and having its end 19 secured thereto in a suitable manner, 75 as by rivet 21. I may and do further provide a suitable lock 26, as shown in Fig. 3, for the purpose of locking the hinged casing or housing 25 so that the mechanism of the carburetor locking valve will be inaccessible to anyone except the owner of the 80 car.

Referring to Fig. 1 there is shown in elevation the tube 22 which extends into the lock housing 25 which is shown in its preferred position relative to carburetor C and manifold M.

The operation of key 5 manually in lock 4 swings the L-shaped arm 6 in the arc of a circle, so as to bring it into or out of 90 operative engagement with the pivotally mounted pressure plate 7, which in turn depresses or releases the bell-crank lever 11, which latter member in turn presses and seats, or releases and opens the double conical locking valve 13, which is positioned to control the supply of fuel and which is normally pressed against the contacting arm of bell-crank 11, by the tension spring 16.

In the form of the invention shown in 100 Figs. 4 and 5 the tube 22 and flexible sleeve 23 leading to the dashboard, are omitted and lock 4 is mounted immediately in joint 18 of casing 20. The latter construction is a simpler but less convenient form of the invention. The latter form will be the less expensive, and from that standpoint the more advantageous, while the form of the invention shown in Figs. 1-3 may be preferred where the standpoint of convenience 105 110

is the main consideration and it is desired to obviate raising of the hood to lock the car.

What I claim is:

5. 1. In a lock for automobiles adapted to control the fuel supply, the combination of a lock and key, means in operative connection with the lock, a pivotally mounted arm actuated by said means, a diaphragm adjacent said arm, a bell crank lever on the other side of the diaphragm and positioned to be actuated by the above described arm, a conical valve in operative engagement with the bell crank lever, resilient means 10 tending to open the valve when released by the bell crank lever, and means for connecting said valve casing with pipes leading to the carburetor and the fuel supply.
15. 2. In a lock for automobiles adapted to control the fuel supply, the combination of a lock and key mounted on the dashboard of the automobile, a flexible operating member connected to and operated by the aforesaid lock, an arm actuated by the flexible 20 operating member, a second arm actuated by the first named arm, said second arm being in engagement with the outer surface of a diaphragm, said diaphragm operating to prevent escape of the fuel, a valve actuating member engaging the inner surface of the diaphragm and positioned to be actuated by the arm which engages the diaphragm on its outer surface, a valve in the 25
30. 3. In combination with the mechanism described in claim 2, a hinged metal housing adapted to completely inclose the valve casing and valve actuating parts in proximity to the valve, and a key-operated lock mounted in said metal housing and arranged to lock said housing, whereby to prevent unauthorized persons from getting access to 35 the valve casing without first breaking the metal housing.
4. In a lock for automobiles adapted to control the fuel supply, the combination of a lock and key mounted on the dashboard 40 of the automobile, a flexible operating member connected to and operated by the aforesaid lock, an L-shaped arm swingable by said flexible operating member, a pivotally mounted arm actuated by said L-shaped 45 arm, a bell crank lever actuated by the aforesaid pivoted arm, a double conical valve, in operative engagement with the bell crank lever, a resilient means tending to open the valve when released by the bell crank lever, 50 a valve casing in which the aforesaid valve and valve actuating parts are mounted, and means for connecting said valve casing with pipes leading to the carburetor and the fuel supply.

CHARLIE C. SHETTERLY.
